UNITED STATES PATENT OFFICE.

HORACE P. OWENS, OF ATLANTA, GEORGIA.

WIRE-STRETCHER.

1,144,310.

Specification of Letters Patent. Patented June 22, 1915.

Application filed August 14, 1914. Serial No. 856,767.

To all whom it may concern:

Be it known that I, HORACE P. OWENS, a citizen of the United States, residing at Atlanta, in the county of Fulton and State 5 of Georgia, have invented certain new and useful Improvements in Wire-Stretchers; and I do hereby declare the following to be a full, clear, and exact description of the invention, such as will enable others skilled 10 in the art to which it appertains to make and use the same.

This invention relates to certain new and useful improvements in devices for stretching wire fences and the like.

15 The object of my invention is to provide an efficient and compact device of this class in which the operating means can be alternately controlled through the action of engaging pawls, thereby assuring a continuous 20 and even pull upon the wire being stretched.

Another object of my invention is the provision of a wire stretching device including in combination a novel frame, post-engaging 25 means formed on said frame, and an operating mechanism positioned within the frame for successively engaging the wire when being stretched.

The invention further consists in the combination and novel arrangement of the several parts hereinafter described and pointed out in the appended claims.

In the drawing: Figure 1 is a side elevation of my improved wire stretching device when in position for stretching a wire fence. Fig. 2 is a plan view of the device showing the position of the two alternating wire-engaging chains, one of which has finished its operation and the other of which 40 has just been given another grip for continuing the operation. Fig. 3 is a vertical sectional view on an enlarged scale, showing the position of the pawls when one of the chain-engaging members is being used. Fig. 45 4 is a plan view thereof, and Fig. 5 is a detail view similar to Fig. 3, illustrating the reverse position of the pawls when the other chain engaging member is being operated.

Referring to the drawings, the present invention 50 comprises a U-shaped frame having a post-engaging means formed thereon, a chain receiving and winding mechanism located in the said frame and means, including a plurality of pawls, for operating the 55 said chain receiving and winding mechanism. The U-shaped frame 1 is provided

with the side bars 2 and 3, the ends of which are preferably enlarged as at 4 and 5 so as to confine the chains, as will be herein-after described. The cross bar 6 connects 60 the two sides and also has extending therefrom a post engaging member 7. As shown, this post-engaging member is square and is provided with a securing bolt 8 for firmly holding the device upon the post 9. Any 65 other design of engaging member, however, can be used, according to the style of securing post found most convenient.

Journalized in the enlarged ends 4 and 5 of the side bars is a cross shaft 10. Secured to the shaft and located in the center thereof is a gear 11. Each side of this gear together with the enlarged ends 4 and 5, forms a receiving station for the respective chains 12 and 13 which are also secured to 70 the shaft 10, see Fig. 4. Positioned within the frame and secured to another cross shaft 14 is a pinion 15 adapted to mesh with the gear 11. Upon one end of this shaft 14 is formed an eye 15' for the reception of a 75 turning bar 16 through which the device is operated. Coöoperating with this operating mechanism, and more particularly the pinion 15, are a plurality of pawls 18 and 19. These pawls are pivoted at 20 and 21 in 80 suitable bearings formed on the side bars and are adapted to alternately engage the pinion 15, as will now be described.

As shown in Fig. 3, the pawl 19 is in engagement with the teeth of the pinion 15, 90 the pawl 18 resting upon the upper surface of the pawl 19 and providing for an effective engagement of the pawl 18 with the pinion 15. Assuming the shaft 14 to be rotated in the direction of the arrow in Fig. 3, 95 the pinion 15 will revolve, the teeth thereof passing beneath the pawl 19, and the large gear 11 will be rotated. As the gear 11 is operated the shaft 10, to which the chains are secured, will be rotated and the chain 12 100 will be wound upon the shaft within its receiving station, thereby effecting the stretching of the wire. As the chain 12 is being wound within its receiving station, the chain 13 is being unwound and paid out, thereby 105 releasing it for the next hold upon the wire in effecting the continuous operation of the device. When the chain 12 has been sufficiently wound in the operation of stretching, the pawl 19 will drop into one of the teeth 110 of the pinion 15 and lock the device against any tendency to release the stretched wire.

The released chain 13 will now be secured to the wire in taking another hold thereon, as shown in Fig. 2. Suitable clips 22 are provided for engaging the wire, but any other desired means may be employed. The chain 13 having been secured to the stretched wire the pawls are now reversed, the pawl 18 engaging the pinion 15 and the pawl 19 resting upon the upper surface thereof, as shown in Fig. 5. In reversing the pawls, the device is prevented from operating by reason of the released chain having been secured to the wire, as will be readily understood. When in this position, the shaft 14 is again rotated in an opposite direction to the arrow above mentioned and shown, and the chain 13 is gradually wound upon the shaft 10 within its receiving station; the chain 12 which has been heretofore wound in the preceding operation being paid out or released.

The post to which the device is attached may be braced as by 23, the said brace being suitably anchored within the ground, as shown. The set screw or bolt 8 also permits of a ready adjustment of the device upon the post in stretching wires at different heights.

While I have shown my device as applied in stretching a wire, I do not limit myself to this use alone, as it may be useful in many analogous arts which properly fall within its adaptation.

From the foregoing it will be obvious that an efficient and practical device is provided, the associated parts of which can be readily manipulated in a minimum amount of time and with a small degree of labor.

What I claim and desire to secure by Letters Patent is:

1. A device of the class described includ-

ing in combination a U shaped frame having a post engaging means provided on one end of said frame, means for stretching the wire including a cross shaft having a gear mounted thereon, a second gear engaging said first mentioned gear, a shaft for said second gear, independent gripping chains secured to the first mentioned shaft upon opposite sides of the first mentioned gear and between the sides of the frame and the sides of the gear, a plurality of gravitating pawls arranged to engage the said second gear alternately in the stretching operation, and means for rotating the same.

2. A device of the class described including in combination a U shaped frame having a post engaging means provided on one end of said frame, means for stretching the wire including a plurality of operating and receiving stations comprising a cross shaft, a gear secured to said shaft, a second gear of less diameter than the first mentioned gear adapted to mesh with said gear, an operating shaft for said second gear, independent gripping chains secured to the cross shaft upon opposite sides of the first mentioned gear and between the sides of the frame and the sides of the said gear, a plurality of gravitating pawls mounted above said second gear and arranged to alternately engage the said second gear in the stretching operation, and means for rotating the same.

In testimony whereof I affix my signature, in presence of two subscribing witnesses.

HORACE P. OWENS.
